UNITED STATES PATENT OFFICE.

CHARLES HENRY BURFORD, OF MEADE, KANSAS.

SAFETY DEVICE FOR FLYING-MACHINES.

1,024,676.

Specification of Letters Patent.

Patented Apr. 30, 1912.

Application filed July 25, 1911. Serial No. 640,404.

To all whom it may concern:

Be it known that I, CHARLES HENRY BURFORD, a citizen of the United States, residing at Meade, in the county of Meade and State of Kansas, have invented certain new and useful Improvements in Safety Devices for Flying-Machines, of which the following is a specification, reference being had to the accompanying drawings:

- 10 This invention relates to new and useful improvements in safety devices for flying machines and more particularly to a device of this character which can be fitted to a flying machine of any make and has for its 15 object to check the fall of the machine when the operator has lost control of the same so that he can gain control of his machine and be able to alight at most any position he should desire.
- 20 Another object of the invention is to produce a device of this character which will possess advantages in points of efficiency, durability, is inexpensive of manufacture and at the same time is simple in construction and operation.

With the above and other objects in view the invention consists in the novel features of construction and the combination and arrangement of parts hereinafter described, 30 pointed out in the claims and shown in the accompanying drawings, in which—

Figure 1 is a fragmentary perspective view of a flying machine showing my safety device applied thereto; Fig. 2 is a side elevation of the device showing the same unfolded and having the form of a parachute; Fig. 3 is a vertical sectional view; and Fig. 4 is a transverse sectional view.

Referring more particularly to the drawings 40 Fig. 1 indicates the frame of the flying machine, which is mounted on the traction wheels 2, said traction wheels being mounted one in front and two at the sides of the frame. Mounted on the frame is a tubular base portion 3 adapted to receive the lower end of a tubular receptacle 4 which is secured to the base by means of the rivets 4' and extends up through the frame work of the machine and projects above the top of 50 the machine, said tube being disposed at an angle of any desired degree, but preferably at that shown in the drawings. Normally disposed in this tubular receptacle 4 is a parachute 5 having a reinforced piece of 55 canvas or other suitable material secured in the top as shown at 6 and all the cords 7 are

secured thereto. A vertically disposed rod 8 is attached to the top of the parachute and passed down through the same and connected to the bottom plate 9, said plate 60 having the cords 10 secured in the outer edge thereof.

A ring 11 is secured to the plate 9 and a rope or cable 12 is secured in said ring and passed down into the tubular receptacle 4 65 where it is wound on a rotatably mounted drum 13 disposed in the lower end of the receptacle 4, said drum being mounted on a transversely disposed shaft 14 having a rectangular end 15 adapted to receive a crank handle to wind up the drum and a ratchet wheel 16 is mounted on the other end of the shaft. A dog 17 is pivotally mounted adjacent the ratchet wheel and adapted to engage the ratchet wheel to hold the drum 70 against backward movement.

Horizontally disposed in the lower end of the tubular receptacle 4 and just above the drum is a circular plate 18 on which is mounted a suitable coil spring 19, which, 80 when the parachute is folded into the tube 4, is compressed by having the plate 9 pressing down on the same. The tube 4 is provided on its upper end with an outwardly turned flange 20 to prevent the cable from 85 being cut when it is being played out.

As shown in Fig. 1 the device is inclosed in the tube ready for flight, the spring being compressed and will force the parachute out when the ratchet 18 is released. When it is 90 desired to release the parachute the operator will grasp the ring 11 which is connected to the dog 17 by means of the cord 21 and by a slight pull will release the drum and allow the coil spring to force the parachute 95 clear out of the tube, there being just enough cable to allow the parachute to pass clear of the tube and when the parachute reaches the end of the cable it will give somewhat of a jerk which will assist in starting the parachute to spread and the machine will be eased down to the ground and will alight without injury to the machine or operator.

From the above description taken in connection with the drawings it will be seen that I have provided a simple and practical device which will check or stop the fall of any flying machine enough to allow the operator to regain control of the machine and 100 alight as he should desire.

While I have shown and described the

2
preferred form of my invention it will be obvious that various changes in the details of construction and in the proportions may be resorted to for successfully carrying my 5 invention into practice without sacrificing any of the novel features or departing from the scope thereof.

Having thus described my invention I claim:

- 10 1. In a device of the character described, the combination of a frame mounted on traction wheels, a tubular base mounted on said frame, a tubular receptacle having its lower end disposed in said base, a parachute 15 disposed in said tubular receptacle, a cable secured to the lower end of said parachute, a drum rotatably mounted in the lower end of said receptacle on which said cable is wound, means for holding said drum against backward movement, and means for forcing said 20 parachute out of the tubular receptacle when said drum is released.
2. In a device of the character described, the combination of a frame mounted on 25 traction wheels, a tubular base mounted on said frame, a tubular receptacle having its lower end disposed in said base, a horizontal shaft disposed in the lower end of said receptacle, a drum mounted on said shaft, a 30 ratchet wheel mounted on one end of said shaft, a dog pivotally mounted adjacent

said wheel and adapted to engage the same to hold said drum against backward movement, a parachute disposed within said tubular receptacle, a cable secured to said 35 parachute and adapted to be wound on the drum, and means for forcing said parachute out of the receptacle when said dog is released from the ratchet.

3. In a device of the character described, 40 the combination of a frame, a tubular base mounted on said frame, a tubular receptacle having its lower end disposed in and secured in said base, a drum rotatably mounted in the lower end of said receptacle, means for preventing backward movement of said drum, a horizontally disposed circular plate mounted in said receptacle just above said drum, a coil spring mounted on said plate, a parachute normally disposed in said receptacle and bearing on said spring, a cable secured to said parachute and adapted to be wound on the drum to hold said spring compressed, means for releasing said drum to allow the coil spring to force the parachute 45 out of the receptacle.

In testimony whereof I hereunto affix my signature in the presence of two witnesses.

CHARLES HENRY BURFORD.
